UNITED STATES PATENT OFFICE.

JOHN L. OSBORNE, OF ROCHESTER, NEW YORK, ASSIGNOR TO JUDSON GOVERNOR COMPANY, OF ROCHESTER, NEW YORK, A CORPORATION OF NEW YORK.

GOVERNOR.

1,190,946.

Specification of Letters Patent. Patented July 11, 1916.

Application filed October 26, 1915. Serial No. 58,023.

To all whom it may concern:

Be it known that I, JOHN L. OSBORNE, a citizen of the United States, and resident of Rochester, in the county of Monroe and 5 State of New York, have invented certain new and useful Improvements in Governors, of which the following is a specification.

This invention relates to speed-governors for engines, and particularly to governors 10 of the centrifugal type, such as are commonly employed in connection with steam-engines.

One object of the invention is to produce a governor having a centrifugal mechanism 15 of a form in which, without complication of construction, provision is made for a wide range of adjustment and of sensitive action, and to this end I employ an arrangement in which the weights have a substantially rectilinear or radial movement toward and from the axis of revolution, while being connected with the parts actuated thereby through a simple arrangement of levers.

Another object of the invention is to produce 25 a centrifugal mechanism which, while inclosed compactly within an oil-tight casing, is at the same time readily adjustable at any time, even while the governor is running, and without opening the casing. To 30 this end I employ a construction in which the centripetal spring of the mechanism is arranged coaxially with the centrifugal mechanism, and is adjustable by means of a member which extends outwardly through 35 the side of the casing, in a manner herein-after described.

Another object of the invention is to improve the valve which is connected with, and actuated by, the centrifugal mechanism 40 of the governor.

In Letters Patent of the United States No. 963,803, granted to me July 12, 1910, I have disclosed a governor provided with a governor-valve, or throttle-valve, in which 45 the rotatable valve-member fits and turns within an outer fixed valve-member.

In accordance with the present invention I have improved the construction of the valve disclosed in my said patent, by re- 50 arranging the parts so that the rotary valve-

member embraces and turns upon an inner fixed valve-member, with resultant advantages which are hereinafter set forth.

In the accompanying drawings: Figure 1 is a side-elevation, partly in vertical section, of a governor embodying the present invention; Fig. 2 is a plan-view in section on the line 2—2 in Fig. 1; Fig. 3 is a front-elevation of the centrifugal mechanism and the case in which it is inclosed, with the front or cover of the casing removed; and Fig. 4 is a horizontal section on the line 4—4 in Fig. 1.

The invention is illustrated as embodied in a governor adapted particularly for use 65 in connection with a steam-engine. The centrifugal mechanism comprises two weights 10, which are rotated in a vertical plane by a connection with a horizontal drive-shaft 11 journaled in a stationary sleeve 12. The 70 shaft carries, at its rear end, a pulley 13 by which it may be belted to the engine which is to be governed.

A sleeve 14, fixed to the forward end of the shaft 11, is provided with two radial 75 guideways, each comprising two parallel arms 15 between which the respective weight 10 is embraced. Each weight is provided with a pair of guide-rollers 16 which engage and move in slots 17 in the 80 inner surfaces of the arms 15, the arrangement being such that the weight may move freely in a radial direction and may also have a limited angular movement, while being restrained against lateral or fore-and-aft movement with respect to the guideway. 85

The inner end of each weight 10 is bifurcated, and provided with a pivot-pin 18 by which it is connected with one arm 19 of a bell-crank lever. The levers are mounted 90 on pivots 20 in brackets 21 projecting integrally from the sleeve 14, and the shorter arm 22 of each bell-crank lever has the form of a gear-segment, the two segments meshing together so that the movements of the 95 levers and of the weights shall be always simultaneous and equal.

The centrifugal tendency of the weights is resisted by a centripetal spring 23, which is arranged coaxially with the shaft 11 and 100

is partly embraced within a recess therein. The forward end of the spring rests against one member 24 of a ball-bearing, the other member 25 of the bearing being engaged by 5 lugs 26 integral with the arms 22. When the weights 10 move outwardly they swing the bell-crank levers in a direction to press the spring 23 rearwardly against the ball-bearing, and thus compress the spring 23, 10 and the bearing permits this pressure to be transmitted, without substantial friction, while the spring remains fixed against rotation.

The rotating parts just described are all 15 inclosed within an oil-tight casing 27, of which the rear portion is integral with the sleeve 12, as shown in Fig. 1, the casing being thus stationary. The inner end of the spring 23 rests against a collar 28, fixed on 20 a rod 29 which projects forwardly through the front of the casing and is screw-threaded for engagement with an adjusting-nut 30. A key and key-way connect the rod 29, against rotation, with the casing, so that rotation of the nut 30 causes a longitudinal 25 movement of the rod, thus varying the degree of compression of the spring 23 for any given position of the weights 10. In this manner the strength of the centripetal 30 spring 23 may be varied at any time to change the normal speed of the centrifugal mechanism.

In my said Patent No. 963,803, I have disclosed a combined governor and regulator 35 for air-compressors in which the centrifugal mechanism is arranged to rotate about a horizontal axis and is combined with a safety stop-mechanism of a peculiar form, and with a governor-valve of a rotary form. 40 In the present apparatus the same general arrangement is employed, and it may be understood that the mechanism, in so far as it is not particularly illustrated and described, may be the same as that of my said 45 patent. Accordingly, the action of the centrifugal mechanism is transmitted to the governor-valve through the intermediation of a sleeve 35 which embraces and slides longitudinally upon the sleeve 12 in which 50 the shaft 11 is journaled. A collar 31 is arranged to slide loosely upon the exterior of the sleeve 14, and this collar 31 has integral extensions 32 which bear against the rear surface of the bearing-member 25. 55 The rear extremity of the collar 31 engages a collar 33 which also slides on the sleeve 14, and this latter collar is provided with studs 34 which slide loosely through openings in the rear wall of the casing 27, 60 and which abut loosely against the forward end of the sleeve 35.

The bearing-sleeve 12 is supported by studs 36, mounted in a fork 37 which is swiveled upon the upper end of a column

38, this column rising from the top of the 65 casing 39 in which the rotary governor-valve is inclosed. The valve is provided with a stem 40 by which it may be rotated, the upper end of the stem being fixed to a short shaft 41 which turns in a bearing 42 70 projecting from the column 38, all as in my said patent.

Fixed to the upper end of the shaft 41 is an arm 43 upon which is mounted a roller 44. This roller is in position to be engaged 75 by a lug 45 which projects from the lower surface of the sleeve 35. The longitudinal movement of the sleeve, produced by its connection with the centrifugal mechanism as above described, causes the lug to engage 80 the roller and move it rearwardly, thus swinging the arm 43 and rocking the shaft 41 and the stem 40 in a direction to move the governor-valve toward closed position.

The opening movement of the governor-valve is produced by means of a spring 47, 85 which is inclosed within a sleeve 46 integral with the arm 43. This spring surrounds and acts against a stem 48 which slides through the sleeve, the pointed end of the 90 stem being seated in a socket in a lug 50 projecting from the bearing 42. The spring 47 is preferably made of only such strength as is necessary to overcome the frictional 95 resistance of the valve and its stem to rotation.

Fig. 1 shows certain features of the safety stop-mechanism including an actuating-spring 51. This mechanism is precisely the same as that in my said Patent No. 963,803, 100 and accordingly is not described herein, it being understood that the movement of the bearing-sleeve 12 in the swiveling fork 37 is for the purposes of the safety stop-mechanism, and that the sleeve 35 has elongated 105 slots through which the studs 36 pass, as shown in Fig. 2, so that these studs do not interfere with the longitudinal movement of the sleeve. They serve, however, to prevent rotation of the sleeve, and thus to maintain 110 the lug 45 in coöperative relation with the roller 44.

Since the movement of the governor-weights 10 is radial, it will be apparent that, in accordance with the laws of centrifugal 115 action, their centrifugal force at any given speed of rotation increases in proportion to their movement outwardly from the axis. From this, and from the slightness of change in angularity of the lever-arms 19 120 resulting from the outward and inward movements of the weights, it follows that the mechanism may be arranged to operate in a nearly isochronous manner throughout all parts of its range of movement. This 12 characteristic permits a wide range of adjustment of the normal speed of the governor—the adjustment produced by rotating

the nut 30—while at the same time permitting the use of a comparatively short centripetal spring. In other words, the tension of the spring may be widely varied in adjusting the governor, while keeping within the range in which the mechanism is sensitive to slight changes in speed.

Another advantage of the peculiar form of the centrifugal mechanism resides in the fact that it permits of incasing the mechanism without the use of a bulky and unsightly casing, so that lubrication of the mechanism is facilitated, while the danger of rapidly mounting exposed parts is eliminated. At the same time, however, the arrangement of the centripetal spring permits the adjusting-means to be brought out at the front of the casing to a position where they are convenient for use at any time, even when the governor is operating.

The novel form of the governor-valve which is actuated by the centrifugal mechanism above described, is shown in Figs. 1 and 4. This valve comprises an inner cylindrical member 54, which is provided with uniformly-spaced vertical slots or ports 55, and an outer cylindrical member 56, which is provided with ports 57 corresponding in position with the ports 55. The inner valve-member is fixed in the casing 39, its lower end being forced or otherwise secured in a seat in the casing. In this manner the casing is divided into two parts, of which the upper annular part communicates with an inlet 52 by which the steam enters the casing, while the lower part is provided with an outlet 53, through which the steam passes to the engine. The outer valve-member 56 is fitted closely upon, but rotatably about, the inner member, and it is provided at the top with a spider 58 which is connected, by a clamping-device 59, with the lower end of the valve-stem 40. This valve-stem passes through an opening in the top of the case, the joint being made steam-tight by a stuffing-box the same as in my said Patent No. 963,803. The passage of steam through the valve is controlled by the registration of the ports 55 and 57, being more or less cut off as the valve-member 56 is rotated to restrict the area of registration of the ports. Since the upper end of the rotary valve-member 56 is open, there is no unbalanced pressure upon this valve-member at any point except that part of its area which is measured by the cross-sectional area of the stem 40. This last area is preferably such that the steam-pressure effective against it is approximately equal to the weight of the rotary valve-member and the stem, and in this way endwise pressure or thrust against the rotary parts is practically eliminated.

One advantage of the present construction of the governor-valve over that shown in

my said patent resides in the fact that it is 65 cheaper to construct. Only the inner surface of the outer valve requires machining or fitting, while only the outer surface of the inner valve-member requires machining, whereas in the previous construction both 70 the inner and the outer surfaces of the fixed valve-member require machining, the outer surface in order to fit it to the valve-casing, and the inner surface in order to fit it to the inner rotary valve-member.

Another advantage of the present construction resides in the fact that the current of steam has no tendency to rotate the rotary valve-member.

In the construction shown in my said 80 patent, when the valve is nearly closed the steam assumes a rotary movement within the rotary valve-member, which under certain conditions has a noticeable tendency to cause rotation of this member toward closed 85 position, and which thus interferes with the sensitive control of the valve by the centrifugal mechanism. By the present construction this tendency is entirely eliminated.

In order to relieve the rotary valve-member 56 of all unbalanced lateral force a baffle-plate 60 is fixed in the valve-casing 39 in such a position as to receive the impact of the current of steam entering through the inlet 52, the steam being diverted laterally 95 by this baffle-plate so as to flow around the valve-member to the several ports therein.

My invention is not limited to the embodiment thereof hereinbefore described and illustrated in the accompanying drawings, but it may be embodied in various other forms within the nature of the invention as it is defined in the following claims.

I claim:

1. A governor having, in combination, a 105 stationary sleeve; a shaft journaled in the sleeve; centrifugal mechanism carried by the shaft; a stationary casing carried at the end of the sleeve and inclosing the centrifugal mechanism; and means, for connecting the centrifugal mechanism with a governor-valve, comprising a sleeve slidable upon the stationary sleeve, and connections, between the sliding sleeve and the centrifugal mechanism, slidable through the wall of the 110 casing.

2. A governor having, in combination, a horizontal shaft; centrifugal mechanism actuated by said shaft; a sleeve concentric with the shaft and movable longitudinally 120 under the influence of the centrifugal mechanism; a vertical rotary valve-member; an arm fixed to the valve-member; and an abutment, on the sleeve, coöperating with said arm to turn the valve-member in consequence 125 of the movement of the sleeve.

3. A governor having, in combination, a stationary sleeve, a shaft journaled in the

sleeve; centrifugal mechanism carried by the shaft; a stationary casing carried at the end of the sleeve and inclosing the centrifugal mechanism; means for connecting the centrifugal mechanism with a governor-valve; a nonrotative rod projecting forwardly through the casing, adapted for engagement

by an adjusting nut; a centripetal spring compressed between a collar on said rod and a movable bearing on said rod; and bell-crank levers connected with said centrifugal mechanism and acting on said movable bearing.

JOHN L. OSBORNE.
